COMBINATION CIGARETTE CASE AND
LIGHTER

Frederick A. Whittaker, Attleboro, Mass., assignor to Marathon Company, Attleboro, Mass., a Corporation of Massachusetts

Application August 31, 1932. Serial No. 631,153

4 Claims. (Cl. 67—7.1)

This invention relates to a combined pyrophoric lighter and cigarette case and pertains principally to the actuating devices for the lighter and their relation to the case.

5 When the case is held in the hand in the most natural and convenient position for use, the thumb most naturally rests at one of the upper corners of the case. An ordinary actuating lever mounted on the case in that position for operation by the thumb would not only be mechanically awkward, but would detract from the design of the case and would also present undesirable projections which would interfere with the use of the article as a pocket case.

It is the principal object of the present invention to provide a finger piece or thumb piece in the very desirable location mentioned, for actuating the lighter, which is free from the 20 objections noted. To this end I make the case with a cut-off corner, and fill the corner space with a collapsing or telescoping or disappearing corner piece, which in normal position constitutes in effect a continuation of the case and 25 virtually forms the corner part of the case itself, but which may be moved or collapsed into the case and when so moved operates the lighter.

In the accompanying drawing:

30 Fig. 1 is a front elevation of a combination cigarette case and pyrophoric lighter;

Fig. 2 is a similar view on a reduced scale showing the case and lighter held in the hand of a user and being operated;

35 Fig. 3 is a front elevation on an enlarged scale of the operating mechanism of the lighter removed from the case;

Fig. 4 is a section on line 4—4 of Fig. 3;

Fig. 5 is a side view of the article viewed 40 from the right of Fig. 1; and

Fig. 6 is a top plan view.

The case consists of a continuous back wall 10, extending across the top as shown at 11, and down the front side at 12. The lighter 45 mechanism is housed within the space between the front wall 12 and the back wall 10 at the top of the case. Below the lighter the case provides a compartment for cigarettes closed by the lid 13, hinged to the case at 14, and held 50 latched by the usual spring catch 15. The upper right-hand corner of the case as viewed in Figs. 1 and 2 is cut off diagonally as shown at 16, providing a corner aperture 17 in the case.

The lighter proper comprises a fuel receptacle 55 18, which may be filled through a screw cap 19,

a burner 20 containing the usual wick extending into the fuel receptacle, a pyrophoric member 21 positioned beside the burner, a serrated friction wheel 22 journaled between a pair of upstanding ears 23, 23, on top of the fuel receptacle 18 and making contact with the pyrophoric member 21, and a snuffer 24 in the form of a cup which fits over the burner 20. The snuffer and friction wheel are both actuated by a lever 25 pivoted at 26 between the two ears 23, 23. The 60 cup 24 is carried by the forward end of the lever 25. A curved rack 27 pivoted to the lever at 28 extends downward in front of and underneath a ratchet wheel 29, which is positioned beside the friction wheel 22 and fastened to the same shaft. 70 The rack 27 is yieldingly pressed against the ratchet wheel 29 by a light wire spring 30 so that the teeth of the rack are normally held in engagement with the teeth of the ratchet 29. When the lever 25 is swung upwardly on its 75 axis 26 the snuffer 24 is lifted from the wick and simultaneously the toothed rack 27, moving upwardly in engagement with the ratchet 29, rotates the friction wheel 22 and causes the 80 sparks to be emitted from the pyrophoric member 21 for lighting the wick.

The rear end of lever 25 is provided with a pin or stud 31 which works in a slot 32 formed in the upper end of a lever 33 whose lower end is pivoted to the fuel receptacle 18 at 34. 85

Lever 33 is shaped to conform to the interior shape of the corner piece 35, to which it is rigidly attached. The corner piece 35 is made in the form of a hollow shell of substantially triangular shape in elevation, and of a size and form complementary to the case so as to fill out or replace the cut-off corner of the case and present an appearance and contour of substantial continuity with the case. The corner piece 35 normally closes the corner aperture 17 of the case, and closely fits in the aperture, but with sufficient clearance so that the corner piece may be manually freely swung or collapsed into the case through the aperture to the position illustrated in Fig. 2 for actuating the friction wheel 90 and snuffer. 100

I claim:

1. A cigarette lighter comprising a casing having rigid wall members providing a compartment in the upper portion of said casing, said casing having a cut-off corner providing a corner aperture in the upper end of the compartment, lighter mechanism including pyrophoric and friction members, a snuffer and actuating means for operating the friction member and snuffer 105 110

housed within said compartment, a complementary corner piece normally closing said aperture and pivotally mounted at its lower end to be swung manually into said compartment through said aperture, and connections between said corner piece and said actuating means for operating the lighter mechanism.

2. A cigarette lighter comprising a casing having rigid wall members providing a compartment in the upper portion of said casing, said casing having a cut-off corner providing a corner aperture in the upper end of the compartment, lighter mechanism including pyrophoric and friction members, a snuffer and actuating means for operating the friction member and snuffer housed within said compartment, a complementary corner piece normally closing said aperture in the form of a hollow shell constituting in effect a corner of said casing, said shell being pivotally mounted at its lower end to be swung into said compartment through said aperture, and connections between said corner piece and said actuating means for operating the lighter mechanism.

25 3. A cigarette lighter comprising a casing having rigid wall members providing a compartment in the upper portion of said casing, said casing having a cut-off corner providing a corner aperture in the upper end of the compartment, lighter mechanism including pyrophoric and friction members, a snuffer and actuating means for operating the friction member and snuffer housed

within said compartment, a complementary corner piece normally closing said aperture in the form of a hollow shell constituting in effect a corner of said casing, a lever rigidly secured within said hollow shell, the lower end of said lever being pivoted within said compartment near the bottom of said corner aperture and constituting the fulcrum on which the shell may be manually swung into the second compartment, and connections between the upper end of said lever and said actuating means for operating the lighter mechanism.

4. A cigarette lighter comprising a casing having rigid wall members providing a compartment in the upper portion of said casing, said casing having a diagonally cut-off corner providing a corner aperture in the upper end of the compartment, lighter mechanism including pyrophoric and friction members, a snuffer and actuating lever for operating the friction member and snuffer housed within said compartment, a complementary corner piece normally closing said aperture in the form of a hollow shell of substantially triangular form, said shell being pivotally mounted at its lower end to be swung manually into said compartment through said aperture, and an arm secured to said shell and projecting inwardly therefrom, said arm having a pin and slot connection with said actuating lever for operating the lighter mechanism when swung inwardly.
